CLAIM

The ornamental design for a rough-in valve, as shown and described.

DESCRIPTION

FIG. 1 is a front, top, right-side perspective view of a rough-in valve in accordance with our new design; FIG. 2 is a rear, bottom, left-side perspective view thereof; FIG. 3 is a front elevational view thereof; FIG. 4 is a rear elevational view thereof; FIG. 5 is a left-side elevational view thereof; FIG. 6 is a right-side elevational view thereof; FIG. 7 is a top plan view thereof; and, FIG. 8 is a bottom plan view thereof.

The broken lines immediately adjacent the shaded area represent the bounds of the claimed design while all other broken lines are directed to environment and are for illustrative purposes only; the broken lines form no part of the claimed design.

1 Claim, 8 Drawing Sheets
